Primary Examiner — Garth Rademaker*Assistant Examiner* — Richard Kearney(74) *Attorney, Agent, or Firm* — Jacobson Holman, PLLC.(57) **CLAIM**

We claim the ornamental design for a finger ring, as shown and described.

DESCRIPTION

FIG. 1 is a front perspective view of a finger ring;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom view thereof.

The broken lines show portions of the ring which form no part of the claimed design.
